VALVE CONTROL FOR PRESSES AND THE LIKE

Thomas F. Stacy, Piqua, Ohio, assignor to The
French Oil Mill Machinery Company, Piqua,
Ohio

Application July 29, 1943, Serial No. 496,602

8 Claims. (Cl. 121—38)

This invention relates to improvements in operating or control valve mechanisms for fluid-pressure-actuated presses and the like, a primary purpose of my invention being to provide a valve mechanism adapted to effect a very high speed of operation of the press with the use of the minimum volume of pressure fluid in order to conserve pressure fluid and avoid the necessity for maintaining or pumping a large quantity thereof.

Another object of the invention is to provide an efficient, practical and desirable operating or control valve mechanism for presses and the like which is of novel, improved construction; which is adapted to effect a rapid initial movement of the press ram or movable member with the minimum use of pressure fluid, and then increase the operating pressure on the press ram or member when it encounters a predetermined resistance to its movement, and a rapid return or pull-back movement of the press ram or member.

Further objects and advantages of the invention will appear from the following specification of the preferred embodiment of the invention, shown in the accompanying drawing, and the novel features of the invention are set forth in the appended claims.

In said drawing, the figure is a schematic view, partly in section, of a press operating valve mechanism embodying the invention, showing by solid lines the positions occupied by the parts during the initial rapid portion of the work stroke of the press ram before the maximum pressure is applied; and indicating by broken lines the positions of the movable valve elements for the application of maximum pressure and for the pull-back or return movement of the press ram.

Referring to the drawing, 10 represents a stationary member or cylinder and 11 the movable ram piston or member of a press actuated by hydraulic or fluid pressure. The chamber 12, or portion of the cylinder at one side or end of the piston, constitutes the work chamber in which the pressure acts on the larger area of this end face of the piston for producing the work stroke of the piston, and the cylinder chamber 13 at the opposite side or end of the piston forms a pull-back chamber 13 in which the pressure acts against the other end face of the piston, which is of smaller area, to pull back or return the piston or movable press member. The work and pull-back chambers are shown as chambers in a single cylinder, but the invention is not restricted to this form of pressure actuating means for the movable press ram or member.

15 represents an accumulator or source of liq-

uid under pressure which is delivered to and exhausted from the press chambers 12 and 13 for operating the press under the control of a valve or device A and valves B and C, which, for convenience of description, are herein respectively designated the operating valve, the main control valve and the auxiliary control valve. The main and auxiliary valves B and C control the passages of the pressure fluid to and from the work and pull-back chambers of the press, and the operating device A serves as a pilot valve for actuating the control valves B and C.

The control valves B and C may be of similar construction each, as shown, comprising a cylindrical casing in which a valve element is adapted to be moved endwise in one or the other direction by fluid pressure in opposed actuating cylinders or chambers, preferably at opposite ends of the valve casing. Referring first to main valve B, its casing 15 forms a central valve chamber 16 and opposite end actuating cylinders 17 and 18, and its movable element comprises a body 19 having spaced lands or enlarged portions 20 and 20a slidably fitting in the valve chamber 16, a reduced central 20 or waist portion and pistons 21 and 22 at its opposite ends, one piston 21 working in the cylinder 17 and the other piston working in the cylinder 18. Pistons 21 and 22 are of different cross sectional areas, the piston 21 being the larger, so that the pressure on this piston can move the valve element to the right, as seen in the drawing, in opposition to pressure on the other piston. The auxiliary control valve C is similar to the valve B, as thus far described, and the corresponding parts are designated by the like reference numerals.

As illustrated, the operating valve A comprises a cylindrical casing 23 in which a movable element, comprising spaced pistons or lands 24 and 25 on a rod or stem, is movable endwise, the rod or stem 26 projecting out of one end of the cylinder to enable actuation of the valve, as by means of a foot pedal or member 27 which when depressed, pushes the movable element inwardly or in one direction, while opposite movement of the element may be effected as by a spring 28, located between the inner end of the movable element and the adjacent end of the valve casing. An intermediate port in the casing of operating valve A is connected by a pipe or conduit 30 with the accumulator, and said valve casing has ports, one connected by a pipe 31 and branches to the actuating cylinders 17 of the main and auxiliary control valves B and C, and the other connected by a pipe or conduit 32 and branches to the opposed actuating cylinder 18 of the control valves

B and C. Said pipe or conduit 31 also connects with the work chamber 12 of the press cylinder.

Main control valve B has an intermediate port connecting by a pipe or conduit 35 with the accumulator, and another intermediate port connected by a pipe or conduit 36 with the work chamber 12 of the press. A pipe or conduit 37 connects a chamber port of main valve B with a chamber port of auxiliary valve C, and the chamber of auxiliary valve C has an intermediate port connected by a pipe or conduit 38 with the pull-back chamber 13 of the press, and another intermediate port connected by a pipe or conduit 39 with the work chamber 12 of the press, as by juncture with the pipe 36. An exhaust pipe or conduit 40 is also connected by branches with the opposite ends of the chamber 16 of the main valve B, and by branches 41 and 42 with opposite end portions of the casing of the operating valve A.

In the pipe 31, between its connections with the two control valves B and C, is a check valve 45 adapted to open freely, as indicated by the arrow, in the direction to admit pressure to the actuating cylinder 17 of the auxiliary valve C. A bypass bleeder passage 46 permits slow leakage or only a restricted passage of pressure liquid through pipe 31 in the opposite direction past this check valve 45 when closed. In the same pipe 31, between its connections with the press chamber 12 and the auxiliary control valve C is a check valve 47 adapted to open freely, as shown by the arrow, in the direction to admit passage of pressure from the work chamber 12 of the press cylinder; and also in the same portion of pipe 31 is a pressure relief valve or device 48 of any usual or suitable construction adapted to open to permit passage of pressure fluid from the work chamber 12 of the press to the actuating cylinder 17 of the auxiliary control valve C when the pressure in work chamber 12 reaches a predetermined value for which the pressure relief valve 48 is set.

The operation of the press operating or control-mechanism may be described as follows: The drawing shows by solid lines the positions of the movable parts of the mechanism when operating valve A has been actuated by depression of its pedal 27 to start the work stroke of the press ram or member. In this position of the operating valve A, liquid is delivered from the accumulator through pipe 30, operating valve casing 23 and pipe 32 to the smaller actuating cylinders 18 of the two control valves B and C, thereby moving and holding their movable elements to the left, as shown in the drawing. Any opposing liquid pressure in the other valve actuating cylinders 17 can exhaust through pipe 31, bleeder bypass 46, operating valve casing 23 and exhaust pipe 42, thus permitting the left hand movement of the control valves B and C. Pressure liquid then will be delivered from the accumulator through pipe 35, casing of main control valve B and pipe 36 to the work chamber 12 of the press to produce a working stroke of the press ram or member. At this time, pipes 38 and 39 and the chamber of the auxiliary valve C connect the pull-back and work chambers 13 and 12 of the press so that liquid can flow freely from the pull-back chamber into the work chamber, thus producing rapid motion of the press piston member in its working stroke. The free flow of the liquid from the pull-back chamber into the work chamber of the press in this way reduces the volume of pressure liquid required to be supplied by the accumulator to produce the working stroke of the press ram and effects a rapid move-

ment of the latter. When, because of increasing resistance of the work to this work stroke of the press ram or member, the liquid pressure in work chamber 12 reaches the value for which the pressure relief valve 48 is set, this valve is opened by the liquid pressure from the work chamber 12 and the liquid will flow past the check valve 47 and pressure relief valve 48 into the actuating cylinder 17 of auxiliary valve C. Since the piston 21 is of larger diameter than the opposing piston 22, the movable element of auxiliary valve C will be moved to the right, as seen in the drawings, to the position indicated by the broken lines. Similar actuation of the main control valve B at this time by the pressure from the work chamber 12 of the press is prevented because the cylinder 17 of main valve B is open to exhaust beyond the check valve 45 and bleeder bypass 46, and main control valve B will remain in the left hand position shown. In this position of the two valves, the liquid will continue to pass from the accumulator to the work chamber 12 of the press through the pipes 35 and 36, as before, but the liquid will discharge from the pull-back chamber 13 through pipe 38, chamber 16 of auxiliary valve C, pipe 37 and chamber of valve B to the exhaust pipe 40 through its branch which connects with the right hand end of control valve B. Full pressure is thus applied to the press ram member to permit the maximum pressure thereon on the work.

When the working stroke of the press ram has been completed, the pedal 27 is released to permit the operating valve element to be moved by its spring to its other or left hand position, indicated by broken lines in the drawing. In this position, operating valve will cut off the supply of liquid from the accumulator through pipes 30 and 32 to the right hand cylinders of control valves B and C and will connect supply pipe 30 with pipe 31, thus delivering the pressure liquid to the left hand cylinder 17 of the main control valve B and shifting the movable element of this valve to the position indicated by broken lines in the drawing. The auxiliary control valve C had already been moved to this right hand position, as before explained, and is there held by admission of pressure from the pipe 31 to the left hand cylinder 17 of auxiliary valve C. In this position of the valves, work chamber 12 of the press will be connected to the exhaust pipe 40 through pipe 36, chamber 16 of main valve B and the left hand branch of the exhaust pipe 40, while liquid will be delivered from the accumulator through pipe 35, chamber 16 of main valve B, pipe 37, chamber of auxiliary valve C and pipe 38 to the pull-back chamber 13 of the press cylinder, thereby effecting a rapid return or movement to the left of the press ram or member. The parts will remain in this position with the press ram in its retracted position until the operating valve is again operated by depression of its pedal to return the valves to the position shown by solid lines in the drawings to effect the next operation of the press.

Upon such subsequent actuation of the operating valve, the pressure liquid will be admitted, as before explained, to the right hand cylinders 18 of control valves B and C, and at this time the left hand cylinder 17 of the main valve B will be connected with the exhaust pipe 40 through the pipe 31 and casing 23 of operating valve A and branch 42 of exhaust pipe, and the left hand cylinder of the auxiliary control valve C will be similarly connected to the exhaust

through pipe 31 and the bleeder bypass 46 of the check valve 45, which will thus permit the pressure on the smaller piston 22 of auxiliary valve C to overcome the pressure on the larger piston 21 thereof and thus restore this valve to the solid line position shown, that is, to the left hand position in the valve casing, thus permitting the working stroke of the press ram as before explained.

I claim as my invention:

1. In an operating mechanism for an hydraulic press or the like having a movable member, a source of liquid under pressure, main and pull-back chambers, and means on which pressure liquid supplied to said chambers acts respectively to produce working and return strokes of said press member, the improved construction comprising a main valve having a movable element controlling ports and passages arranged to supply liquid from said supply source to said main press chamber and to exhaust liquid from said main and pull-back chambers, an auxiliary valve having a movable element controlling ports connecting with a port in the main valve and with said main and pull-back chambers, said main and auxiliary valves in a first position of their said elements connecting said main press chamber with said supply source and connecting said pull-back chamber with said main chamber for effecting a rapid work stroke of the press member, and said valves in said first position of said main valve element and in a second position of said auxiliary valve element connecting said main chamber with said supply source and opening said pull-back chamber to exhaust for increasing pressure on the press member, and said main and auxiliary valves in the second position of their elements opening said main chamber to exhaust and connecting said pull-back chamber with said supply source for returning said press member, first pressure actuated devices for moving said main and auxiliary valve elements to said first position and second pressure actuated devices for moving said main and auxiliary valve elements to said second position, an operating valve having a movable element controlling ports and passages arranged to supply liquid from said supply source to and exhaust liquid from said pressure actuated devices for said main and auxiliary valves, said passage to said second pressure actuating devices also connecting with said main press chamber, means which controls said passage and allows flow of pressure liquid from said main press chamber to said second actuating device of said auxiliary valve when the movable press member encounters a predetermined resistance but prevents flow through said passage to said main chamber, and a check valve which controls said passage between said second actuating devices for said main and auxiliary valves and allows free flow of liquid to the actuating device of said auxiliary valve and has a bleeder bypass which allows restricted opposite flow of liquid.

2. In an operating mechanism for an hydraulic press or the like having a movable member, a source of liquid under pressure, main and pull-back chambers, and means on which pressure liquid supplied to said chambers acts respectively to produce working and return strokes of said press member, the improved construction comprising a main valve having a movable element controlling ports and passages arranged to supply liquid from said supply source to said main press chamber and to exhaust liquid from said main

and pull-back chambers, an auxiliary valve having a movable element controlling ports connecting with a port in the main valve and with said main and pull-back chambers, said main and auxiliary valves in a first position of their said elements connecting said main press chamber with said supply source and connecting said pull-back chamber with said main chamber for effecting a rapid work stroke of the press member, and said valves in said first position of said main valve element and in a second position of said auxiliary valve element connecting said main chamber with said supply source and opening said pull-back chamber to exhaust for increasing pressure on the press member, and said main and auxiliary valves in the second position of their elements opening said main chamber to exhaust and connecting said pull-back chamber with said supply source for returning said press member, first pressure actuated devices for moving said main and auxiliary valve elements to said first position and second pressure actuated devices for moving said main and auxiliary valve elements to said second position, an operating valve having a movable element controlling ports and passages arranged to supply liquid from said supply source to and exhaust liquid from said pressure actuated devices for said main and auxiliary valves, said passage to said second pressure actuating devices also connecting with said main press chamber, a check valve and a pressure relief valve which control said passage and prevent liquid flow therethrough to said main press chamber but allow flow of pressure liquid from the main press chamber to said second actuating device of said auxiliary valve when the movable press member encounters a predetermined resistance, and a check valve which controls said passage between said second actuating devices for said main and auxiliary valves and allows free flow of liquid to the actuating device of said auxiliary valve and has a bleeder bypass which allows restricted opposite flow of liquid.

3. In an operating mechanism for an hydraulic press or the like having a movable member, a source of liquid under pressure, main and pull-back chambers, and means on which pressure liquid supplied to said chambers acts respectively to produce working and return strokes of said press member, the improved construction comprising main and auxiliary valves each having a reciprocable element with opposed actuating pistons of different pressure areas working in correspondingly different pressure cylinders, said main valve element controlling ports and passages arranged to supply liquid from said supply source to said main press chamber and to exhaust liquid from said main and pull-back chambers, and said auxiliary valve element controlling ports connecting with a port in the main valve and with said main and pull-back chambers, said main and auxiliary valves in a first position of their said elements connecting said main press chamber with said supply source and connecting said pull-back chamber with said main chamber for effecting a rapid work stroke of the press member, and said valves in said first position of said main valve element and in a second position of said auxiliary valve element connecting said main chamber with said supply source and opening said pull-back chamber to exhaust for increasing pressure on the press member, and said main and auxiliary valves in the second position of their elements opening said main chamber to exhaust and connecting said pull-back chamber with said supply source for returning said press member, first pressure actuated devices for moving said main and auxiliary valve elements to said first position and second pressure actuated devices for moving said main and auxiliary valve elements to said second position, an operating valve having a movable element controlling ports and passages arranged to supply liquid from said supply source to and exhaust liquid from said pressure actuated devices for said main and auxiliary valves, said passage to said second pressure actuating devices also connecting with said main press chamber, a check valve and a pressure relief valve which control said passage and prevent liquid flow therethrough to said main press chamber but allow flow of pressure liquid from the main press chamber to said second actuating device of said auxiliary valve when the movable press member encounters a predetermined resistance, and a check valve which controls said passage between said second actuating devices for said main and auxiliary valves and allows free flow of liquid to the actuating device of said auxiliary valve and has a bleeder bypass which allows restricted opposite flow of liquid.

to exhaust and connecting said pull-back chamber with said supply source for returning said press member, an operating valve and passages constructed and arranged to supply liquid from said source to and exhaust liquid from said actuating cylinders for moving said main and auxiliary valve elements to said first and second positions, said passage to the cylinders of larger area also connecting with said main press chamber, means which controls said passage and allows flow of pressure liquid from said main press chamber to the actuating cylinder of said auxiliary valve when the movable press member encounters a predetermined resistance but prevents flow through said passage to the main press chamber, and a check valve which controls said passage between its connections with the actuating cylinders for said main and auxiliary valves and allows free flow of liquid to the actuating cylinder of said auxiliary valve and has a bleeder bypass which allows only restricted opposite flow of liquid.

4. In an operating system for a fluid actuated motor of the type having advancing and retracting chambers, a working element operated by pressure alternately in said chambers, and a source of actuating fluid under pressure, that improvement in the control of the movement of said element which comprises a main valve and an auxiliary valve each having two conditions of operation, and pilot controlled means for operating said valves into said conditions, connections by which said auxiliary valve when in one condition connects said chambers directly to each other and when in another condition disconnects said chambers from each other and connects said retracting chamber to said main valve, connections by which said main valve when in one condition connects said source to said advancing chamber and connects said auxiliary valve to exhaust, and in another condition connects said source to said auxiliary valve and connects said advancing chamber to exhaust, a control valve, and direct connections independent of said main and auxiliary valves between said source, said control valve and said pilot controlled means for causing operations of said main and auxiliary valves upon operation of said control valve, and means automatically responsive to the pressure in said advancing chamber for causing operation of said auxiliary valve into its said another condition while the pressure in said advancing chamber is above a predetermined pressure.

5. In an operating system for a fluid actuated motor of the type having advancing and retracting chambers, a working element operated by pressure alternately in said chambers, and a source of actuating fluid under pressure, that improvement in the control of the movement of said element which comprises a main valve, an auxiliary valve, connections controlled by said auxiliary valve for alternately connecting said chambers directly together, and for breaking said direct connections and connecting said retracting chamber to said main valve, connections controlled by said main valve for connecting said source alternately to said advancing chamber and to said auxiliary valve, and for venting any connections not connected to said source, a control valve, means controlled by said control valve and operating independently of said main and auxiliary valves for either causing operation of said main valve to connect said source to said advancing chamber and operation of said auxiliary valve to connect said chambers directly, or for

operating said main valve to vent said advancing chamber and connect said source to said auxiliary valve, and for operating said auxiliary valve to break said direct connection between said chambers and connect said retracting chamber to said source through said main valve, and means automatically responsive to fluid pressure in said advancing chamber for separately causing operation of said auxiliary valve to break the direct connection between said chambers whenever the fluid pressure in said advancing chamber is above a predetermined pressure.

6. In an operating system for a fluid actuated motor of that type having advancing and retracting chambers, a working element operated by pressure alternately in said chambers, and a source of actuating fluid under pressure, that improvement in the control of the movement of said element which comprises means for connecting said source alternately to said chambers and venting the chamber not connected to said source, means for breaking the connection from said source to said retracting chamber and instead connecting said retracting chamber directly to said advancing chamber, selectively controlled means operating independently of said first and second mentioned means to cause operation of said first means to connect said source to said advancing chamber and concurrently of said second means to directly connect said chambers, or to cause operation of said first means to vent the connection to said advancing chamber and connect said source through said first means to said retracting chamber, and means responsive to the fluid pressure in said advancing chamber and free of the control of said controlled means, for forcibly operating said second means to break the direct connection between said chambers whenever the fluid pressure in said advancing chamber is above a predetermined pressure, in any condition.

7. In an operating mechanism for a fluid actuated motor or the like having a movable member, a source of fluid under pressure, main and pull-back chambers, and means on which pressure fluid supplied to said chambers acts respectively to produce working and return strokes of said motor member, the improved construction comprising a main valve having a movable element controlling ports and passages arranged to supply fluid from said supply source to said main chamber and to exhaust liquid from said main and pull-back chambers, an auxiliary valve having a movable element controlling ports connecting with a port in the main valve and with said main and pull-back chambers, said main and auxiliary valves in a first position of their said elements connecting said main press chamber with said supply source and connecting said pull-back chamber with said main chamber for effecting a rapid work stroke of the motor member, and said valves in said first position of said main valve element and in a second position of said auxiliary valve element connecting said main chamber with said supply source and opening said pull-back chamber to exhaust for increasing pressure on the motor member, and said main and auxiliary valves in the second position of their elements opening said main chamber to exhaust and connecting said pull-back chamber with said supply source for returning said motor member, fluid actuated operating means including a control valve and fluid connections independent of said main and auxiliary valves for shifting said main and auxiliary valve elements to

said first and last mentioned relative positions, and means actuated under control of fluid pressure from said main chamber when the movable motor member encounters a predetermined resistance for effecting said second mentioned relative positions of said main and auxiliary valve elements.

8. In an operating mechanism for a fluid actuated motor having a movable member, a source of fluid under pressure, main and pull-back chambers, and means on which pressure fluid supplied to said chambers acts respectively to produce working and return strokes of said motor member, the improved construction comprising a main valve having a movable element controlling ports and passages arranged to supply fluid from said supply source to said main chamber and to exhaust fluid from said main and pull-back chambers, an auxiliary valve having a movable element controlling ports connecting with a port in the main valve and with said main and pull-back chambers, said main and auxiliary valves in a first position of their said elements connecting said main chamber with said supply source and connecting said pull-back chamber with said main chamber for effecting a rapid work stroke of the motor member, and said valves in said first position of said main valve element and in a second position of said auxiliary valve element connecting said main chamber with said supply source 30

5 and opening said pull-back chamber to exhaust for increasing pressure on the motor member, and said main and auxiliary valves in the second position of their elements opening said main chamber to exhaust and connecting said pull-back chamber with said supply source for returning said motor member, first pressure actuated devices for moving said main and auxiliary valve elements to said first position and second pressure actuated devices for moving said main and auxiliary valve elements to said second position, an operating valve having a movable element controlling ports and passages arranged to supply fluid from said supply source to and exhaust fluid from said pressure actuated devices for said main and auxiliary valves, said passage to said second pressure actuating devices also connecting with said main press chamber, means which controls said passage and allows flow of pressure fluid from said main press chamber to said second actuating device of said auxiliary valve when the movable motor member encounters a predetermined resistance but prevents flow through said passage to said main chamber, and means which controls said passage between said second actuating devices for said main and auxiliary valves and allows free flow of fluid to the actuating device of said auxiliary valve and allows only restricted opposite flow of fluid.

THOMAS F. STACY.
